FIG. 5.

WITNESSES

J. F. Phillips
Alas F. Garner Jr.

A technical drawing of a U-shaped metal component. The top horizontal bar is labeled '16.4'. The vertical leg on the left is labeled '37'. The vertical leg on the right is labeled '38'. The depth of the U-shape is labeled '46'. The top horizontal bar has a small '9' written above it. The entire U-shape is hatched with diagonal lines. To the right of the U-shape, there is a vertical line with the numbers '17' and '22' written above and below it respectively.

ATTORNEYS

UNITED STATES PATENT OFFICE.

CHARLES W. KIRBY, OF STRONGHURST, ILLINOIS.

GRAVE-FILLER.

1,123,892.

Specification of Letters Patent.

Patented Jan. 5, 1915.

Application filed September 19, 1914. Serial No. 862,550.

To all whom it may concern:

Be it known that I, CHARLES W. KIRBY, a citizen of the United States, and a resident of Stronghurst, in the county of Henderson and State of Illinois, have invented a new and useful Improvement in Grave-Fillers, of which the following is a specification.

This invention relates to grave filling machines and embodies improvements on the grave filler forming the subject of my application filed July 18, 1914, Serial No. 851,751.

One of the principal objects of the invention is to provide a grave filling machine including a knock-down box having a side gate with removable means for reducing the exit opening of the box.

Another object of the invention is to provide a grave digger of the type set forth and having a side gate with a removable board or guard to prevent the collecting of earth between the box and gate.

With these and other objects in view which will become apparent as the description proceeds, the invention resides in the construction, combination and arrangement of parts hereinafter more fully described and claimed, and illustrated in the accompanying drawing in which like characters of reference indicate like parts through the figures, of which—

Figure 1 represents a perspective view of my improved grave filling machine, Fig. 2 represents a vertical sectional view taken transversely thereof, Fig. 3 represents a perspective view of one of the removable partitions, Fig. 4 represents a fragmentary horizontal sectional view taken on the plane indicated by the line 4—4 of Fig. 2, Fig. 5 represents an enlarged fragmentary sectional view taken on a common plane with Fig. 2.

The grave filler on which the present invention is an improvement, includes a drag comprising a floor 6 supported by runners 5.

A box or body is supported on the floor and includes end walls 9 and a rear wall 10. Secured to the latter near its ends are a pair of uprights 11 which form the rear corner posts of the box. Uprights 12 are secured to the rear wall intermediate the posts 11. Near the front edges of end walls 9 are secured the front corner posts 17. All of the uprights and posts have their lower ends

reduced as at 13 to fit in openings in floor 6 whereby to removably maintain the walls in position.

In order to prevent accidental displacement of the rear edges of walls 9 the rear wall 10 is provided with guide strips 15 between which and the uprights 11, the rear edges of walls 9 are disposed. Strips 16 provided on the inner sides of the end walls 65 are adapted to engage against the corner posts 11 for further bracing and guiding the end walls. Diagonally disposed braces 19 removably connected to the uprights 12 and to the front corner posts 17, serve to brace 70 the end and rear walls.

The front wall of the box includes a folding gate or chute 22 and sections 23 and 24. The latter are removably maintained in position by means of pins 32 and hooks 33 and 34. The gate when closed rests at its lower edge in the front rabbeted edge 25 of the floor 6. Hinges 26 have their upper leaves secured to the gate and have their lower leaves 28 removably engaging in staples 29 80 secured to the front edge of the floor 6. Substantially arcuate segments 30 are secured to the ends of chute 22 and are adapted to guide the earth in its movement from the box during the process of emptying the latter. When the chute or gate is in closed position the segments or plates 30 engage the outer faces of end walls 9. Hooks 31 are provided on the end walls and are adapted to engage segments 30 for maintaining the gate in closed position.

The improvement wherein the present invention resides lies in the construction and arrangement of the partitions 35 and the fender or guard 36. The partitions are 95 adapted to be positioned one at each end of the machine and are for the purpose of reducing the opening through which the dirt may find its exit in filling smaller graves than ordinarily. Each partition comprises 100 a substantially rectangular board 46 disposed longitudinally of the machine adjacent the front thereof. The inner edges of the boards are adapted to be slidably positioned between the front corner uprights 17 105 and guide strips 37 disposed on end walls 9 in spaced relation to said uprights, as indicated in Fig. 4.

A brace 38 is secured on the inner face of each partition and engages against guide 110 strip 37 when the partition is in place, as indicated in the drawing. A second brace 39

is secured to the inner face of each partition near the outer edge thereof and projects slightly above the upper edge of the partition as at 40. A hook or other suitable fastening device 41 is carried by each brace 39 near its upper end and supports one end of a chain or similar flexible connection 42. The opposite end of the chain is carried by a hook 43 secured to one of the uprights 12 near its upper end. In order to prevent lateral movement of the outer or free ends of the partitions, each of them is provided on its outer face with a retaining plate 44 extending at its lower end below the lower edge of the partition. Said plate is adapted to be engaged in a slot or recess provided in the floor 6, when the partition is in position. As indicated in Fig. 1, the partitions are adapted to reduce the size of the discharge opening of the machine. Chains 42 prevent lateral movement of the upper portions of the partitions due to the weight of the dirt within the box. The fender 36 is adapted to prevent the collection of earth between gate 22 and floor 6. It is disposed longitudinally of the box and is of a length substantially equal to the distance between the corner uprights 17. Hinges 45, similar to hinges 26, are carried by the fender near its ends, and the lower or free leaves of said hinges are adapted to engage recesses cut in the floor 6, whereby the fender may be removably secured in position. When in upright position the fender extends between the corner uprights 17 so that gate 22 may fold flush against them, and when in extended position, as indicated in Figs. 1 and 2, the fender folds outwardly over the rabbeted edge 25, thus bridging the opening occurring between gate 22 and floor 6. The fender is adapted to be used continuously with the machine, but the partitions are to be used only when a smaller grave is to be filled, and at other times may be removed from the machine so that earth may be discharged from the box through the entire length of the opening.

Although I have described the preferred embodiment of my invention, I may desire to make such changes in the construction, combination and arrangement of parts as do not depart from the spirit of the invention and the scope of the appended claims.

I claim:

1. The combination in a grave filler of a floor, a box mounted thereon, said box including end walls having corner uprights at their forward edges, said box having means whereby an opening may be formed between

the corner uprights, a gate hingedly connected to the flooring adjacent the opening in the box, said gate when in raised position adapted to lie flush against said corner uprights, a fender, means for removably disposing said fender between said uprights along the opening, said fender when said gate is in outward position adapted to be folded outwardly to bridge the opening occurring between said gate and floor.

2. The combination in a grave filler of a box adapted to have an opening formed along one side, removable partitions adapted to be positioned adjacent the open side for partially closing the same, a gate hingedly connected to the floor of the box, and a fender disposed in the open side of the box and between the partitions and gate, and adapted to prevent entrance of dirt between the gate and floor.

3. The combination in a grave filler, of a box, a gate disposed along one side thereof and adapted when folded outwardly to form a discharge opening extending the entire length of the boxing, means for preventing entrance of earth between the gate and boxing, and removable means for adjusting the size of the opening.

4. The combination in a grave filler, of a box having end walls, corner uprights secured to the end walls, removable means adapted to form a discharge opening for the box between the corner uprights, guide strips secured to the end walls in spaced relation to the corner uprights, removable partitions disposed within the box and engaging along one edge between said guide strips and corner uprights, plates carried by said partitions and depending below the latter and adapted to engage in recesses provided in the floor of the box, and means connecting said partitions with the opposite wall of the box for bracing the partitions.

5. A grave filler comprising a box, a gate carried thereby and adapted to be swung for forming a discharge opening, means to prevent entrance of dirt between the gate and box when the former is in open position, partitions adapted to be disposed within the box longitudinally of the opening for regulating the length of the latter, and means for detachably connecting the partitions with the box.

CHARLES W. KIRBY.
